UNITED STATES PATENT OFFICE

1,973,601

APPARATUS FOR HANDLING FIRE EXTINGUISHING MATERIALS AND FOR PRODUCING FIRE EXTINGUISHING FOAM

Fisher L. Boyd, Philadelphia, Pa., assignor to National Foam System, Inc., Philadelphia, Pa., a corporation of Pennsylvania

Application October 23, 1931, Serial No. 570,552

6 Claims. (Cl. 169—15)

This invention relates to apparatus for the extinguishment of fires and more particularly to an apparatus for facilitating the handling of the materials employed in the production of fire extinguishing foam.

In my United States Letters Patent No. 1,785,723, granted December 16, 1930, is disclosed an apparatus for and method of continuously producing fire extinguishing foam. In connection with this patented apparatus, the method employed in producing the fire extinguishing foam consists in simultaneously introducing different substances into separate flowing streams of water and then causing the streams to be united at a point in proximity to the place of application of the foam, the fire extinguishing foam being produced due to the chemical reaction which takes place when the substances in solution are intermingled. The substances which are preferably employed in the production of the fire extinguishing foam are aluminum sulphate and bicarbonate of soda and a suitable stabilizing agent.

In the extinguishment of fires it is imperative that a continuous supply of fire extinguishing foam be produced during the continuance of the fire. While this may be effected by continuously introducing manually into the separate hoppers of the foam producing apparatus the foam producing ingredients, it has been found much more effective and convenient to employ an apparatus of the character disclosed in my co-pending application Serial No. 350,470, filed March 28, 1929. In this application is disclosed the apparatus for handling the foam forming ingredients consisting of a main storage chamber adapted to maintain in separate relation the dry foam producing ingredients, in combination with means for permitting the ready discharge of these substances into the hoppers of the foam producing apparatus. This material handling apparatus not only did away with the necessity for manually pouring the foam producing substances into the hoppers of the foam generator, but it also facilitated the continuity of supply of the substances to the generator.

It is among the general objects of this invention to improve and increase the efficiency of operation of the material handling apparatus of the character disclosed in my aforesaid co-pending application.

A more specific object of the present invention is to provide an improved valve structure for the discharge outlets of the storage chamber whereby to greatly facilitate the free discharge

of the foam forming substances from within said chamber.

Still another object of the invention is the provision of means for preventing the foam forming substances as discharged from the storage chamber from overflowing from the hoppers of the foam generator when said substances reach predetermined levels in said hoppers, said means being further operative to prevent the further discharge of the foam forming substances from the storage chamber while the hoppers of the foam generator are filled to predetermined capacity.

Still another important object of the invention is the provision of means for preventing the establishment of a vacuum within the storage chamber such as would preclude the free discharge of the foam producing substances therefrom, this means being automatically operative upon opening the discharge valves of the storage chamber.

Other objects of the invention and advantages resulting from the details of construction thereof will be apparent more fully hereinafter.

The invention consists substantially in the combination, construction, location and relative arrangement of parts, all as will appear more fully hereinafter, as shown in the accompanying drawings and as finally pointed out in the appended claims.

In the said accompanying drawings:—

Figure 1 is a side elevational view of the apparatus constructed in accordance with and embodying the principles of the present invention, the apparatus being shown positioned in discharging relation with respect to the hoppers of a foam producing apparatus;

Figure 2 is an end elevational view of the apparatus;

Figure 3 is a vertical sectional view of the bottom portion of the material handling apparatus shown in Figure 2;

Figure 4 is a vertical sectional view taken on the line 4—4 of Figure 3;

Figure 5 is an end elevational view of the air vent controlling means;

Figure 6 is a view corresponding to Figure 5 but taken at right angles with respect thereto, the valve structure for the air vent being shown in vertical section; and

Figure 7 is a sectional view of the cam plate for operating the valve controlling the air vent.

Referring now to the drawings and more particularly to Figures 1 and 2 thereof, it will be observed that the apparatus for facilitating the

handling of the foam forming ingredients is shown in discharging position with respect to the foam generator, designated generally by the reference numeral 10. For a detailed description of the construction and operation of this foam generator 10 reference is herein made to my aforesaid Letters Patent No. 1,785,723, it being sufficient for the present purposes to point out that this generator generally comprises a pipe or 10 conduit 11 for supplying water from a source (not shown) through a V-connection 12 to a pair of conduits 13 and 14. The conduits 13 and 14 are preferably united at a point in proximity to the place of application of the fire extinguishing foam. Respectively associated with the conduits 13 and 14 are a pair of hoppers 15 and 16, these hoppers being respectively adapted to receive the foam producing substances in the manner and for the purposes set forth in my 15 Letters Patent aforesaid. It will be observed that the hoppers 15 and 16 are arranged in side by side relation, the upper ends thereof being open and maintained separate from each other by means of a vertically extending partition 17.

20 In accordance with the principles of the present invention, the foam producing materials which are supplied to the hoppers 15 and 16 are stored in a large storage chamber 18 which is suitably supported by a trolley structure 19 upon an overhead track 20. This track 20 is of sufficient length to support a plurality of storage chambers 18 and is arranged in such manner that these storage chambers may be successively positioned in discharging position with respect to the foam chamber 10. It will be understood 25 that one foam generator of the character designated by the reference numeral 10 is provided for each overhead track 20. Thus, during the course of a fire, the first storage chamber 18 suspended from the overhead track 20 is shifted into position immediately above and in discharging relation with respect to the foam generator. When the foam forming substances have been 30 entirely discharged from this storage chamber 18, it is moved along the track 20 to a point beyond the foam generator whereupon a second storage chamber is moved into position immediately above and in discharging relation with respect to the generator. As many storage chambers as 35 may be desired may be suspended from a single overhead track so as to provide for a continuous and uninterrupted supply of foam forming substances to the particular generator which is associated with that track. This arrangement not 40 only eliminates the necessity for the manual pouring of the foam producing chemicals into the hoppers of the generator but it also simplifies the control of the equipment as a whole, since only one man is necessary for the successful operation thereof.

45 As was stated above, the foam forming substances are of such character that when brought together in solution a fire extinguishing foam is produced. These substances are in the form of dry powdered acid and basic salts, one of these salts being supplied to the hopper 15 and the other to the hopper 16 of the foam generator. In order to maintain these substances in separated 50 relation within the storage chamber 18, the latter is divided by a central partition 21 into a pair of separate storage compartments 22 and 23. The lower ends of these compartments 22 and 23 respectively terminate in funnel sections 24 and 25 each of which is provided with an outlet opening 26. Each outlet opening 26 is controlled by

55 a vertically movable valve structure 27 the construction of which will now be described.

As appears most clearly in Figure 3, the discharge opening 26 for each of the storage compartments 22 and 23 is flanged, as at 27'. Secured to this flange by means of bolts 28 is an annular valve seat 29, the outer peripheral edge or rim of this valve seat being provided with a circumferentially extending shoulder 30 for a purpose to be presently described. The valve 27 is substantially in the form of a downwardly dished plate the upper or convex surface of which is provided with a covering 31 of rubber or other such resilient material. Secured to and extending axially through the valve 27 is a valve stem 32 the upper end of which is bifurcated, as at 33. The valve is supported upon the stem 32 between a nut 34 and a spring-pressed disk 35, the arrangement being such that when the valve stem 32 is drawn upwardly the valve 27 will be drawn more or less tightly against its seat 29, the material 31 being compressed between the metallic body of the valve and the metallic seat 29.

60 In order to insure the simultaneous supply of the foam forming substances respectively contained within the compartments 22 and 23 of the storage chamber, means are provided for simultaneously actuating the valves controlling the discharge openings of said compartments 22 and 23. In order to attain this end, a shaft 36 is projected commonly through the funnel sections 24 and 25 of the storage container 18. This shaft 36 is suitably journaled within bearings 37 and 38 and is adapted to be oscillated by means of an operating arm 39 secured to the exteriorly projecting end of the shaft 36. Suitably keyed to the shaft 36 are a pair of eccentric disks 40 and 41, the eccentric disk 40 being located within the funnel section 24 and the eccentric disk 41 within the funnel section 25. Operatively associated with each of the eccentric disks 40 and 41 is an eccentric strap 42 having an eccentric rod 43. The lower ends of these eccentric rods 43 are respectively joined to the bifurcated ends 33 of the valve stems 32 by pins 44. These pins 44 are preferably of substantial length so as to effectively serve as means for agitating the powdered substances contained within the funnel sections of the compartments 22 and 23 and so loosen the same to insure their ready discharge therefrom. From the foregoing it will be seen that when the operating handle 39 is rotated from the position shown in the figures through an angle of 180° both of the valves controlling the discharge openings in the bottoms of the compartments 22 and 23 will be opened to their fullest extent.

65 As appears most clearly in Figures 1 and 2, the container 18 is suspended from the overhead track 20 so that the discharge outlets for the compartments 22 and 23 are disposed in a substantially horizontal plane arranged slightly above the top edges of the hoppers 15 and 16 of the foam generator. The relative arrangement of the suspended container with respect to the dual ejector is such as to permit the former to be shifted readily into discharging position above the hoppers 15 and 16. In order to preclude any possibility for the powdered chemicals discharged from the compartments 22 and 23 into the hoppers 15 and 16 from flowing over the top edges of the latter, the funnel sections 24 and 25 are each provided with a depending skirt or boot 45 formed of canvas or like flexible material.

70 These boots 45, which respectively extend cir-

cumferentially about the discharge outlets 26-28, are provided with beaded upper edges 46 adapted to snugly fit about the annular shoulders 30 formed in the valve seats 29. Any suitable means 5 may be provided for removably securing the boots 45 to the valve seats. The boots extend downwardly below the horizontal plane of the discharge openings to an extent sufficient to permit their projection into the interior of the hoppers 10 15 and 16 when the container 18 is shifted into the position shown in Figure 1. Due to the flexible character of the material of which the boots are formed, the boots offer no impediment to the free movement of the container 18 relatively to 15 the foam generator. On the other hand, these boots serve most effectively to prevent the powdered foam producing substances from overflowing the top edges of the hoppers 15 and 16, it being apparent that when these hoppers are 20 filled to an elevation approximating that of the bottom ends of the boots the further discharge of the chemicals into the hoppers is immediately interrupted. The boots 45 thus serve effectually to control the rate of discharge of the chemicals 25 from the compartments 22 and 23 during the period that the valves 27 are open.

Inasmuch as the compartments 22 and 23 are normally sealed throughout except at the bottom ends thereof when the valves 27 are open, a 30 vacuum may be created in the top of each of the compartments as the chemicals are discharged therefrom. This vacuum may be of sufficient degree to slow up or impede the free discharge of the powdered chemical. To counteract 35 this, the apparatus is provided with means operative automatically upon opening the valves 27 to introduce air under atmospheric pressure into the void formed within each compartment as the chemical is discharged therefrom. This 40 air-venting means generally comprises a conduit having a branch 47 extending vertically along one side of the apparatus and terminating in a horizontal branch 48 extending interiorly of the compartments 22 and 23. As appears most 45 clearly in Figure 2, the branch 48 of the conduit is arranged immediately beneath the top of the container 18 and is provided with a pair of outlets 49 and 50 respectively in communication with the compartments 22 and 23.

The bottom end of the vertical branch 47 of 50 the conduit is connected to a valve unit 51 (see Figure 6) having the usual intake and outlet ports 52 and 53, the latter being in communication with the conduit. A valve 54, which normally 55 maintains the port 53 closed to the atmosphere, is provided with a valve stem 55 laterally offset from and paralleling the eccentric shaft 36. A spring 56 tends to maintain the valve in closed position. Secured to the eccentric shaft 36 exteriorly of the container 18 is a circular cam plate 57. This plate 57, which is rotatable with the shaft 36 upon actuation of the operating arm 39, is of a diameter sufficient to permit the engagement therewith of the air-vent valve stem 55. The inner surface of the plate 57 is inclined 60 in such manner that upon rotation of the plate the inclined surface thereof will cause the valve stem 55 to be shifted against the force of the spring 56 to open the valve 54 and so permit air to pass through the conduit 47-48 into the compartments 22 and 23. (See Figures 5 to 7). It will be understood, of course, that the angular relation between the cam plate 57 and the eccentric shaft 36 is such that when the latter 65 is oscillated into position for closing the main

valves 27, the cam plate will permit the air-vent valve 54 to be closed by the action of spring 56. Conversely, when the main valves 27 are opened, the air-vent valve is simultaneously opened to permit air under atmospheric pressure to pass into the interior of the compartments 22 and 23 so as to facilitate the discharge of the chemicals therefrom.

It will be understood that the invention as hereinbefore described is susceptible of various changes and modifications without departing from the real spirit or general principles thereof and it is accordingly intended to claim the same broadly, as well as specifically, as indicated by the appended claims.

What is claimed as new and useful is:—

1. In an apparatus for handling fire-extinguishing materials, in combination, hopper means for receiving foam-forming chemicals which are adapted to be introduced into flowing water whereby to produce fire-extinguishing foam; a storage chamber for receiving the chemicals to be supplied to said hopper means, said storage chamber being provided with a bottom discharge outlet; means for positioning said storage chamber immediately above and in discharging relation with respect to said hopper means; and means associated with said discharge outlet and extending freely into the top of said hopper means when said storage chamber is in discharging relation to the hopper means for precluding the overflow of said chemicals from said hopper means.

2. In an apparatus for handling fire-extinguishing materials, in combination, an open-topped hopper for receiving a dry powdered chemical to be dissolved in a stream of water; an elevated track arranged above said hopper; a storage chamber suspended from and movable along said track into position immediately above said hopper, said chamber being provided in the bottom end thereof with a valve-controlled discharge outlet; and a flexible jacket embracing said discharge outlet and extending freely into the top and below the upper edge of said hopper when said storage chamber is in discharging relation to the hopper means for precluding the overflow of the chemical from said hopper.

3. In an apparatus for handling fire-extinguishing materials, in combination, a dual container for receiving in separated relation dry foam-forming ingredients capable upon reacting with each other in the presence of a solvent to produce foam; a dual hopper for separately receiving and introducing said ingredients into a solvent therefor; an elevated track from which said dual container is suspended and along which it is movable into discharging relation with respect to said dual hopper, said container being provided with separate valve-controlled discharge outlets, and means associated with said outlets for precluding the overflow from said dual hopper of the ingredients supplied thereto from said container.

4. In an apparatus for handling fire-extinguishing materials, in combination, a dual container for receiving in separated relation dry foam-forming ingredients capable upon reacting with each other in the presence of a solvent to produce foam; a dual hopper for separately receiving and introducing said ingredients into a solvent therefor; an elevated track from which said dual container is suspended and along which it is movable into discharging relation with re-

- spect to said dual hopper, said container being provided with separate valve-controlled discharge outlets, and means associated with said outlets for precluding the overflow from said 5 dual hopper of the ingredients supplied thereto from said container, said means being in the forms of flexible sleeves adapted to extend downwardly into and below the top edges of the hoppers of said unit during the operation of discharging said ingredients from said dual container into said dual hopper.
6. In an apparatus for handling fire-extinguishing materials, in combination, a storage chamber divided into a pair of separate compartments for respectively receiving acid and basic foam-forming ingredients, each of said compartments being provided with a bottom discharge outlet, an oscillatable shaft extending transversely through the bottom portions of said compartments above said discharge outlets, a valve operatively associated with each outlet, and eccentric means on said shaft and connected to said valves such that upon oscillation of said shaft said valves are actuated in unison to control the discharge of said ingredients from said compartments. 80
7. In an apparatus for handling fire-extinguishing materials, in combination, a storage chamber divided into a pair of separate compartments for respectively receiving acid and basic foam-forming materials, each of said compartments being provided with a normally sealed top and a bottom discharge outlet, a valve operatively associated with each outlet for controlling the discharge of the materials therethrough, a vent leading from atmosphere into the interior of each 85 compartment above the top surface of the material contained therein, a valve in said vent, and means operative to commonly actuate said outlet valves and said vent valve whereby all of said valves are opened and closed simultaneously. 90
8. In an apparatus for handling fire-extinguishing materials, in combination, a storage chamber divided into a pair of separate compartments for respectively receiving acid and basic foam-forming materials, each of said compartments being provided with a normally sealed top and a bottom discharge outlet, a valve operatively associated with each outlet for controlling the discharge of the materials therethrough, a vent leading from atmosphere into the interior of each 95 compartment above the top surface of the material contained therein, a valve in said vent, and means operative to commonly actuate said outlet valves and said vent valve whereby all of said valves are opened and closed simultaneously. 95
